UNITED STATES PATENT OFFICE.

HENRY F. CLARK, OF POUGHKEEPSIE, NEW YORK.

CARTRIDGE.

SPECIFICATION forming part of Letters Patent No. 310,650, dated January 13, 1885.

Application filed September 13, 1884. (No model.)

To all whom it may concern:

Be it known that I, HENRY F. CLARK, of Poughkeepsie, in the county of Dutchess and State of New York, have invented an Improvement in Cartridges, of which the following is a specification.

Cartridges for breech-loading fire-arms have been made with a metallic case or shell having a bullet within the forward end and lubricating material within the shell and around the point of the bullet. In other instances the bullet has been surrounded by a patch formed of a strip of paper, and this has been inserted at the end of the cartridge-case and lubricating material applied between the base of the bullet and wads that rest upon the powder. In shooting with cartridges of these characters I find in practice the following difficulties: Where the lead bullet comes in contact with the rifling of the barrel, the lead is liable to adhere and be scraped off into such grooves, notwithstanding the lubricating material upon the point of the bullet. Where the paper patch is used, the friction causes the patch to break and to rub off and foul the barrel, and the grease and wads following the same do not remove the difficulty. Besides this, the grease is liable to injure the powder.

My invention has been made for removing or preventing difficulties that I have encountered in extensive practice in rifle teams and otherwise. I make use of a bullet that is provided with a patch composed of a strip of paper tightly surrounding the bullet and secured in any suitable manner. I prefer the patched bullet shown in my Patent No. 286,387, and I insert this bullet into a metallic case that extends as far as the end of the bullet, or nearly so, and I fill in the space around the point of the bullet and within the case with a suitable lubricating material, such as tallow or other material. The patch may become saturated with the grease to a greater or less extent, and when the ball is fired the grease lubricates the patch itself and causes it to pass through the barrel with great facility and accuracy,

and the patch itself is not injured in its passage through the barrel, and the patched bullet cleans out the barrel in the most perfect manner, and leaves the barrel with a thin coating of lubricating material that prevents the gases and smoke adhering to the metal; hence these substances are removed by the passage of the next patched bullet, and the barrel is kept in perfect order even in very hot weather.

In the drawings, Figure 1 is a longitudinal section of the cartridge, and Fig. 2 is a separate elevation of the patched bullet.

The bullet *a* is to be surrounded with the patch *b*, of paper, the same being applied in any convenient manner. The shell *c* is of any desired size, shape, or length; but under all circumstances it receives within it the patched bullet, with the point of the bullet about in line with the end of the shell *c*. The space around the conical end of the bullet and the shell is filled with lubricating material, *d*, such as tallow or other suitable substance. The tallow lubricates the barrel and the patch as the bullet is driven through the barrel, and it effectually prevents injury to the barrel by the leading, and insures the proper passage of the paper patch without the same being disintegrated; hence the bullet is not in any way diverted in its flight, and the surface of the bullet remains perfectly smooth and true. The patch is separated, and falls off as soon as the bullet leaves the barrel. The forward end of the cartridge-shell may be straight, as shown, or slightly contracted around the grease.

I claim as my invention—

The combination, with the cartridge-shell, of a bullet having a paper patch around the same, and lubricating material introduced in the shell around the point of the ball, substantially as set forth.

Signed by me this 10th day of September, A. D. 1884.

H. F. CLARK.
